Office Action dated Jan. 6, 2016, issued in counterpart Japanese application No. 2015-015240 (1 page).

Primary Examiner — Darlington Ly

(74) Attorney, Agent, or Firm — Westerman, Hattori, Daniels & Adrian, LLP

(57) **CLAIM**

The ornamental design for a motorcycle front side cowl, as shown and described.

DESCRIPTION

FIG. 1 is a right side elevation view of a motorcycle front side cowl showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a front and right side perspective view thereof; and,

FIG. 7 is a rear and right side perspective view thereof.

The broken lines in the drawings illustrate portions of the motorcycle front side cowl that forms no part of the claimed design.
